UNITED STATES PATENT OFFICE.

GEORGE W. KILDOW, OF YATES CENTER, KANSAS.

CORN-HEADER.

1,213,502.

Specification of Letters Patent.

Patented Jan. 23, 1917.

Application filed April 22, 1915. Serial No. 23,269.

To all whom it may concern:

Be it known that I, GEORGE W. KILDOW, a citizen of the United States, residing at Yates Center, in the county of Woodson and State 5 of Kansas, have invented a new and useful Improved Corn-Header, of which the following is a specification.

This invention relates to a device for cutting the heads from Kafir corn, sugar cane 10 and the like, and more particularly to a device of this character attached to a board adapted to be substituted for the end gate of a farm wagon or it may be secured to the end gate.

15 The object of the invention is to so construct a device of this character that it may be easily operated by one man and which will effectively hold the grain in position while being cut.

20 With the above and other objects in view, the invention consists of certain novel features of construction, combination and arrangement of parts to be more fully described and claimed.

25 In the accompanying drawings: Figure 1 is a rear view of an end gate equipped with this improved cutter; Fig. 2 is a horizontal section taken on the line 2—2 of Fig. 1; and Fig. 3 is a transverse section taken on the 30 line 3—3 of Fig. 1.

In the embodiment illustrated the device constituting this invention is shown applied to an end gate 1 of ordinary construction having the usual transverse cleats 2 spaced 35 from the ends thereof to assist in retaining it in operative position, but obviously it may be secured to any suitable support.

30 This improved cutting device comprises a grain retaining or rest bar 3 preferably 40 constructed of steel which is secured to the outer face of the gate 1 at the upper edge thereof and provided with large teeth 4 which project above said gate edge and performs the double function of a grain rest 45 and as one member of a knife guide. A bar 5 arranged parallel with the bar 3 forms the other knife guide and is secured to the gate 1 by bolts 6 and 7 at its opposite ends. On the bolts 6 and 7 are arranged spacing 50 elements 8 in the form of washers to hold said bars spaced a sufficient distance to permit the knife 10 to be described to enter between them. The bolt 6 is arranged

in the path of the free end of the knife to form a stop for limiting the downward 55 or closing movement of the knife, the knife having a notch 10' at its free end for engaging said bolt.

The knife 10 is fixed at one end to one end of a lever 11 and disposed at an acute 60 angle thereto as shown in Fig. 1 with its cutting edge 9 arranged toward the lever. The portion of this lever 11 to which the knife is secured is normally arranged parallel with and below the bar 5 and is designed to engage the lower edge of said bar 5 for limiting the opening movement 65 of the knife. The teeth 4 on bar 3 are inclined toward the fulcrum of knife 10 so that when the knife is forced down into 70 cutting engagement with the grain, the latter will be held against slipping.

The bolt 7 which connects one end of the bars 3 and 5 with the gate 1 passes also through the inner end of knife 10 adjacent 75 its connection with lever 11, and forms a fulcrum therefor and for the lever 11, said blade having an opening in which the spacer 8 on bolt 7 fits and forms a wear sleeve or bearing for the blade. The free or front 80 end of the lever 11 is offset laterally outward to position it away from the gate 1 when the device is applied. A coiled spring 12 is secured at one end to the rear end of lever 11 at one side of its fulcrum and at its other 85 end to a bracket 13 secured to the gate 1 in a plane below said lever, and exerts its tension to raise the knife and hold it in open position as shown in Fig. 1.

A knife closing device is shown in the 90 form of a stirrup 13' having a connecting rod 14 extending upwardly therefrom and provided at its free end with a laterally extending eye 15. The stirrup 13' and its connector 14 are preferably made from a single 95 rod bent to form the stirrup, one end of said rod having an eye 16 through which the rod 14 passes. Another rod 17 depends from the offset end of lever 11 opposite to that to which the spring is attached, and extends 100 through the eye 15 of the rod 14 and has a laterally extending eye 18 at its free end which is slidably engaged with said rod 14, said rod passing through said eye. A clamp 19 engages the two rods 14 and 17 and is 105 held in engagement therewith by a set screw

or bolt 20. It will thus be seen that the connection between the lever and the stirrup may be adjusted to vary the relative positions of said members at the will of the operator.

In the use of this device, the parts being as shown in Fig. 1, a bundle of grain is placed across the toothed bar 3 below the knife 10 and is held against slipping by the teeth 4 of said bar. The operator then presses the knife 10 by placing his foot in the stirrup 13' and exerting downward pressure thereon, whereby the knife is closed against the tension of its spring and severs the heads from the stalks, the former dropping into the wagon body and the latter outside. When pressure is removed from the

stirrup the spring 12 returns the knife to normal open position.

I claim:

A heading device comprising a bar with means at each end for spacing it from a suitable support, a lever having an off-set portion, a cutting blade rigidly attached at an angle to or near one end of said lever and pivoted on one of the spacing means of said bar, and operating means for said lever, said off-set portion of the lever being out of the plane of the said bar.

G. W. KILDOW.
